UNITED STATES PATENT OFFICE.

JOHN M. CHRISTOPHER, OF BALTIMORE, MARYLAND, ASSIGNOR OF ONE-HALF TO WILLIAM C. LUDWIG, OF SAME PLACE.

SAND-BOX FOR CARS.

SPECIFICATION forming part of Letters Patent No. 507,066, dated October 17, 1893.

Application filed January 28, 1893. Serial No. 460,480. (No model.)

To all whom it may concern:

Be it known that I, JOHN M. CHRISTOPHER, a citizen of the United States, residing at Baltimore, Maryland, have invented certain

5 Improvements in Sand-Boxes for Street-Railway Cars, of which the following is a specification.

The object of my invention is to discharge sand either in a wet or dry condition or sand

10 that contains large stones as will hereinafter fully appear.

In the further description of the said invention which follows reference is made to the accompanying drawings forming a part

15 hereof and in which—

Figure 1, is an exterior side view of a part of a street railway car to which my sand box is attached. Fig. 2 is a partly sectional side view of the sand box on an enlarged scale.

20 Fig. 3 is a front view of the same, and Fig. 4 a top view of Fig. 2.

Similar letters of reference indicate similar parts of the drawings marked thereon.

Referring to the drawings, A is the car and

25 B the sand box which is rectangular in cross section. At the top it is provided with a flange a which is adapted to bolt under the car as shown in Fig. 1. At the front of the box it curves inward so as to contract it near

30 the bottom. It also has an opening c herein-after described.

C is a double cut off which consists of a curved plate d adapted to enter the opening c to close the box and at the rear rests

35 against a lug e on the inside of the same. From the curved plate leads a rib f which is provided with a boss g at each side thereof situated on a shaft h the ends of which are on the walls of the box. Beyond this boss

40 the rib f extends down, and cast to it is another plate i which also serves to close the box when the curved plate is open. By this means the box is closed at all times so as to prevent the waste of sand.

45 It will be seen that sand boxes heretofore in use all have very small discharge openings, and if the sand is wet it becomes banked,

or if large stones should be mixed with the sand it would stop the flow of the same until such obstructions be removed, but with

50

my invention it is operative at all times for the reason that I employ a very large discharge opening and the double cut off thereby gagging a certain quantity of sand to be discharged at a time.

55

The rib at the front terminates into an arm k for a purpose hereinafter described. To this arm k is attached a link D the other end of which is connected to an arm l of a bell crank E pivoted to a lug F dependent from the bottom of the car. The other arm m of the bell crank is secured to one end of a rod G. The other end is fastened to the hand lever H. Through the agency of the lever, rod, bell crank and link the rib f receives a movement carrying the curved plates d and i which opens one and closes the other.

60

The side of the sand box near the top is fitted with a filling door I. This door serves

70

as a funnel when open. It is provided with sides n shown in dotted lines in Fig. 3.

75

J is an agitator which consists of a bar o pivoted on a rod within the box. The upper end is provided with transverse pins p and the lower end q divided into two downwardly

projecting prongs r and s. These prongs

serve in the moving of the braker.

The curved plate d is furnished with a toe piece t and it will be seen that in the movement

80

of the curved plate the toe piece will strike the prong s and carry it forward until the toe piece can pass when the other prong will be carried down, and as the curved plate returns the prongs are carried back into their first position shown in Fig. 2. The agitator may however consist of a bar pivoted in a slot in the curved plate as shown in dotted lines in Fig. 2, which would have a vertical and horizontal movement.

90

The plate i is fitted with a spout u. This spout as shown in the drawings moves with the plate i but it may be attached to the sand box thereby making it stationary.

I claim as my invention—

In a sanding device for street railway cars
the combination of an exterior sand box hav-
ing an exterior filling opening, a cut off to
5 open and close alternately combined with an
agitator so arranged as to be moved as the
cut off is opened or closed thereby agitating

the sand and preventing packing of the same
in the box, substantially as specified.

Baltimore, Maryland, January 17, 1893.

JOHN M. CHRISTOPHER.
